UNITED STATES PATENT OFFICE.

LAWRENCE F. KRIES, OF BALTIMORE, MARYLAND, ASSIGNOR TO WESTINGHOUSE ELECTRIC & MANUFACTURING COMPANY, A CORPORATION OF PENNSYLVANIA.

SWITCH MECHANISM.

Application filed October 6, 1920. Serial No. 415,076.

To all whom it may concern:

Be it known that I, LAWRENCE F. KRIES, a citizen of the United States, and a resident of Baltimore, in the city of Baltimore and State of Maryland, have invented a new and useful Improvement in Switch Mechanism, of which the following is a specification.

My invention relates to switch mechanism and particularly to enclosed entrance switches for controlling electric current delivered to factories, apartments, residences and like buildings.

An object of this invention is to provide a switch box having a switch compartment and a fuse compartment, each provided with a separate cover so controlled by the switch mechanism that the cover closing the fuse compartment is locked in closed position so long as the switch mechanism is in closed position, and that the cover closing the switch compartment is locked in closed position so long as the switch is in open position, if desired.

Another object is to provide a switch box having the above characteristics wherein the switch-operating mechanism may be locked and sealed in "off" or open position, thereby locking the cover closing the switch compartment in closed position without interfering with the opening movement of the cover closing the fuse compartment.

A further object is to provide a switch box having the above characteristics wherein the interlocking mechanism between the covers and the switch mechanism is simple, durable and inexpensive to manufacture, and wherein the switch mechanism serves to retain the covers for the switch compartment and the fuse compartment in closed position when the switch is in an open position intermediate extreme closed and opened positions.

Another object is to provide a switch box wherein the cover closing the switch compartment is provided with an indicator visible from the exterior of the box and actuated by the switch mechanism, for the purpose of indicating "On" and "Off" positions of the switch.

Another object is to provide a switch box wherein the cover for the fuse compartment is provided with fuse receptacles for containing extra fuses which are accessible when the cover is in open position.

Another object is to provide a switch box wherein the fuse and switch panel is so supported in spaced relation with the bottom of the box that certain conductors and terminals entering the box may be accommodated beneath the panel.

A further object is to provide a switch box wherein the potential conductors entering the fuse compartment and leading to the potential coil of the meter are not accessible in the fuse compartment, but are connected to a terminal at a point within the switch compartment.

When new wiring installations are made, several different agencies are involved in the operation, these agencies being the wiring contractor, the electric service company and the wiring inspector. It is not always expedient for these agencies to operate simultaneously, and the service company may desire to connect the meter and main switch with the service line before the wiring throughout the system is completed, in which event it is necessary to guard against the premature closing of the main switch controlling the current to the wiring system until the wiring has been completed and the inspector has approved of the installation.

In order to provide an entrance switch having the proper safe guards, I have provided the apparatus with a cover-and-switch-mechanism interlocking arrangement having the above recited characteristics. When the service company has installed the meter and the enclosed main switch, as specified above, the switch may be locked and sealed in open position wherein the cover closing the switch and the live entrance terminals is locked in closed position. The operating mechanism is provided with suitable sealing means which may be broken only by an authorized wiring inspector. Therefore, current cannot be turned into the system until after the inspector has broken the seal and closed the switch.

The wiring contractor may, at such times, gain access to the fuse compartments and may insert the required fuses and connect the dead-meter terminals without exposing any live parts. The interlocking arrangement is such that, when the switch has been closed by an inspector, the cover closing the fuse compartment is locked in closed position. The cover closing the switch compartment

ment may be opened at this time for the purpose of inspection. This cover may be locked and sealed exteriorly of the housing, as it is intended that this cover be opened 5 only by authorized persons.

In the event that the service company desires to discontinue the service, the operating handle may be sealed in an intermediate position wherein the switch is in open position 10 and wherein the operating mechanism prevents opening of both the fuse compartment and the switch compartment.

The above recited objects, as well as others that will be apparent throughout the 15 further description of the apparatus embodying my invention, are attained by means of the switch mechanism hereinafter described and illustrated in the accompanying drawings, wherein:

20 Figure 1 is a longitudinal section through the housing showing the switch mechanism in side elevation, with the switch in closed position.

25 Fig. 2 is a view similar to that shown in Fig. 1, with the switch shown in open position.

Fig. 3 is a view similar to Figs. 1 and 2 showing the switch and the housing covers in open position.

30 Fig. 4 is a transverse longitudinal section through the housing taken on the line IV—IV of Fig. 3, showing the switch mechanism in plan view.

Fig. 5 is a top plan of a fragment of the 35 switch-compartment cover showing the indicator mechanism.

Referring to the drawings, the apparatus includes a housing having a bottom wall 5, end walls 6 and 7 and side walls 8 and 9.

40 Within the housing is disposed a fuse and switch insulating panel 10 that is so mounted in spaced relation with the bottom 5 upon supports 11, that a space 12 is provided beneath the panel for the accommodation of 45 conductors, such as the meter-potential conductors 13, and others which enter the box through perforations 14 in the end walls adjacent the panel. Upon the panel 10 are mounted three sets of stationary switch-jaw

50 members 15 in which are pivoted movable knife-blade members 16 having their free ends connected by an insulating bar 17. The switch-blade members are adapted to be simultaneously moved into engagement with 55 separate switch-jaw members 18 that are positioned opposite the jaw members 15 and to which the service conductors 19, which enter the housing through the perforation 14, are attached by means of the threaded 60 nuts 20. For the purpose of providing ample space in which heavy-duty service conductors 19 may be located, the end 7 of the box is provided with an extension 19' to which the usual conduit is attached.

65 At the opposite end of the panel 5, three

sets of terminal clips 21 and 22 are located, for receiving the fuse elements 23. The clips 21 and the switch jaws 15 are connected by metallic-conductor strips 24 and the clips 22 are connected by means of threaded nuts 70 25 to conductors 26, which enter the box through perforations 14.

A partition 27 divides the housing into a switch compartment 28 and a fuse compartment 29, the former being closed by means 75 of a hinged cover or door 30 that is provided with flange members 31 which extend interiorly of the housing. Pivot screws 32 extend through the said flanges and are secured to the side walls of the housing, thereby forming a hinge connection about which the door or cover may be turned to open or to closed position. A cover or door 33 that is provided with inwardly-depending ears 80 or webs 34 is so pivoted to the side walls of 85 the housing by means of screws 35 that it may be turned to open and to closed position. The inner face of this cover is provided with a series of clips 33a and 33b for detachably retaining several extra fuses 90 which are made accessible, when the cover is in open position.

The switch members 16 are moved to open and to closed position by means of a pair 95 of operating rods 36 that slide longitudinally of the housing in guide slots 37 provided in the end wall 6 and the partition 27 adjacent the upper edges thereof. A pair of bell-crank lever arms 38 are pivoted upon laterally-extending supports 39 that are 100 mounted, respectively, on the side walls 8 and 9 which carry the pivot pins 40. The inner ends of the rods 36 are pivoted at 41 to one arm of the bell-crank levers. The pivot pins 41 carried by the rod 36 operate 105 in the slots 42 provided in the said arms. Movement of the rods 36 to the right turns the arms 43 of the bell-crank lever 12 in a clockwise direction, which movement is translated to the switching members 16 for 110 the reason that the free ends of the arms 43 are joined to the insulating bar 17. The outer ends of the rods 36 are connected by means of an operating handle 44.

From the foregoing, it is apparent that the 115 switch is moved to the closed position illustrated in Fig. 1 by movement of the operating handle toward the adjacent end of the housing, and that the switch is moved to the open position, as shown in Fig. 2, by movement of the handle away from the housing.

An object of this invention is to so interlock the switch mechanism with the covers 30 and 33 that, when the switch is in closed position, the cover 33 closing the fuse compartment is locked in closed position, and, when the switch mechanism is in open position, the cover closing the switch compartment is locked in closed position. The flanges 31 of the cover 30 are provided with 120 125 130

arcuate grooves 45 that are disposed concentric with respect to the axis of rotation of the bell-crank arms 38, into which lateral projections 46 carried at the extremities of the arm 43, project when the arms are moved to their open position, as shown in Fig. 2. The relative arrangement of the flanges and the projections is such that, when the switch is in closed position, the projections 46 lie clear of the groove 45 and permit opening movement of the cover 30. Opening movement of the arms 38, however, moves the projections 46 into the grooves 45 and thereby prevents opening movement 15 of the cover so long as the arms 38 remain in open position.

In order to maintain the fuse-compartment cover 33 in closed position when the switch is open, the cover is provided with an extension 47 which extends beyond the pivot screws 35 and, consequently, swings inwardly when the cover is moved into open position. When the rods 36 are in their closed position, wherein the switch is in its closed position, opening movement of the cover is prevented by reason of the engagement of the cover extension 47 with the upper edges of the rods. The cover 33, therefore, cannot be opened until the rods 36 are moved to open position, wherein the notches 48 provided in the upper edges of the rods are brought to a position directly opposite to the axis of rotation of the cover. At such times, the cover 33 may be opened without interference with the operating rods 36. In order to limit the movement of the rods so that the notches 48 will occupy their position in which opening movement of the cover is permitted, stops 49 are carried by the rods that are adapted to engage the partition 27 and limit the opening movement thereof.

The rods 36 are provided with perforations 50 so located that, when the rods are in their open position, the perforations lie exteriorly of the end wall 6. The perforations are designed to receive a locking pin 51, as shown in Fig. 4, which serves to retain the operating rods 36 in open position. The locking pin 51 is provided with a perforation 52 through which a seal 53 may be inserted to prevent unauthorized withdrawal of the locking pin 51. The cover 30 is retained in closed position when the switch is closed, by the rod 51 which is passed through perforations 54 provided in the outwardly-extending clips 55 which are secured, respectively, to the side walls 8 and 9.

When the service company desires to discontinue the service of a customer, it has usually been the practice to disconnect the service wires exteriorly of the building. This operation may be obviated providing suitable provision is made to seal the service box with the switch in open position. For

this purpose, the handle rods 36 are provided with perforations 63 that register with perforations 64 in the clips 56 when the switch is moved to an open position intermediate the extreme opened and closed positions. The pin 51 is inserted through the perforations 63 and 64 and the rods 36 locked against longitudinal movement. When the rods 36 occupy this position, the cover 33 is thereby locked by reason of the engagement of the extension 47 with the upper edges of the rods 36, and the cover 30 is locked in closed position by the extensions 46 which, at this time, register with the groove 45 in the side members of the cover. 80

In order that the position of the switch may be indicated when the cover 30 is closed, the cover is provided with an opening 57 (Figs. 1, 2 and 5) beneath which a slide member 58 is supported in a guide member 59 that is secured to the underside of the cover. This slide is movable longitudinally and is provided with the legends "On" and "Off" that are adapted to register with the openings 57 when the switch is in closed and open positions, respectively. The slide is provided with inwardly-projecting end webs 60 and 61 that project into the path of an upwardly-projecting extension 62 carried on the inner end of the rods 36. When the cover is in closed position, the extension 62 projects between the webs and moves the slide 58 to the left when the switch is moved to extreme open position. The extension does not engage the web 60 until the switch 90 is nearly in closed position, but moves the slide to the right during the final closing movement of the switch. It will be apparent, therefore, that, when the switch is in closed position, the legend "On" is visible 100 through the opening, and when the switch is in open position, the legend "Off" is visible. 105

It will be observed that the base 10 is spaced from the bottom of the box for the purpose, as has been previously stated, of providing space beneath the panel for various conductors entering the box. The advantage of this construction resides in the fact that the potential wires 13 leading from terminal connections 63, located in the 110 switch chamber, may be passed through the panel and between it and the bottom of the box, to the conduit (not shown) thereby making them inaccessible from the fuse chamber. The customer, therefore, is precluded from attaching a "jumper" to the potential wires for the purpose of short-circuiting the meter coils. A further advantage of having the panel spaced from the bottom of the housing resides in the 115 fact that service leads may enter the box at the sides or at the fuse end of the box instead of at the switch end, and located beneath the panel. The sides of the box are preferably provided with "knock-outs" 130

(not shown) adjacent the bottom of the box through which the service leads may enter the box at any desired point.

The operation of the switch mechanism is as follows: When the service company installs the meter in the wiring system the entrance terminals are connected to the switch terminals or jaws and the switch is then moved to the open position, shown 10 in Fig. 2, with the switch-compartment cover 30 locked in closed position by the projections 46. Access, therefore, cannot be had to the switch compartment. The locking pin is then inserted through the 15 perforations 50 in the rods 36 and the pin sealed in position. When the switch is in open position, access may be had by the wiring contractor to the fuse compartment for the purpose of connecting the fuse-clip 20 terminals to the wiring system and inserting the fuses in their respective clips. The switch is thus held open until the wiring inspector is ready to turn in the current. In order to do so, the inspector removes 25 the locking pin 51 and moves the switch member to closed position. The pin thus removed is then inserted in the clip 55 and sealed in locking position by the inspector who also seals the fuse-compartment 30 cover by means of a seal 56 which is inserted through perforations 57 and 58 provided in the cover 33 and the end wall 6, respectively. The switch is free to be opened or closed until the box is sealed by the 35 inspector.

While I have described and illustrated but one embodiment of my invention, it will be apparent to those skilled in the art that various changes, modifications, substitutions, additions, and omissions may be made 40 in the apparatus described without departing from the spirit and scope of the invention, as set forth by the appended claims.

I claim as my invention:

45 1. Switch mechanism comprising a housing having a switch compartment and a fuse compartment, a separate movable cover for closing each of the said compartments, a movable switch member in the switch 50 compartment, a fuse member in the fuse compartment, and means for moving the switch member to open and to closed position adapted, when in closed position, to prevent opening movement of the cover 55 closing the fuse compartment and to permit opening movement of the cover closing the switch compartment, and, when in open position, to permit opening movement of the first said cover and to prevent opening 60 movement of the last said cover.

2. Switch mechanism comprising a housing having a switch compartment and a fuse compartment, a separate movable cover for each of the said compartments, a movable switch member in the switch compartment,

ment, a fuse member in the fuse compartment, and means for preventing opening movement of the said cover of the switch compartment when the switch is open.

3. Switch mechanism comprising a housing having a switch compartment and a fuse compartment, a separate movable cover for closing each of the said compartments, a switch mechanism within the housing movable to open and to closed position having means interlocking with the said covers whereby the cover closing the fuse compartment is locked in closed position when the switch mechanism is in closed position and the cover closing the switch compartment is locked in closed position when the switch mechanism is in open position.

4. Switch mechanism comprising a housing having a switch compartment and a fuse compartment, a separate movable cover for closing each of the said compartments, a switch mechanism within the housing movable to open and to closed position having means interlocking with the said covers whereby movement of the said mechanism to alternative positions alternately locks the said covers in closed position.

5. Switch mechanism comprising a housing having an opening, a switch therein accessible through the said opening, a cover for closing the said opening, and means carried by the cover and interlocking with the said switch when the latter is in open position for preventing opening movement of the cover.

6. Switch mechanism comprising a housing having an opening, a switch therein accessible through the said opening, a movable cover for closing the said opening, means carried by the cover and interlocking with the said switch when the latter is in open position for preventing opening movement of the cover, and means for locking the switch in open position.

7. Switch mechanism comprising a housing having a fuse compartment and a switch compartment, a separate movable cover for each of the said compartments, a movable switch member in the switch compartment, means carried by the cover for the switch compartment and interlocking with the said switch when the latter is in open position for preventing opening movement of the cover, and operating means for the switch for moving the switch to open and to closed position, so interlocking with the cover closing the fuse compartment when the switch is in closed position that opening movement of the said cover is prevented by the said operating means.

8. Switch mechanism comprising a housing having an opening therein, a knife-switch member pivotally mounted in the housing, a cover for closing the opening in the housing hinged thereto, an arcuate inter-

locking member carried by the cover and projecting into the housing, a projection extending from the switch member adapted to engage the arcuate interlocking member 5 when the switch is in open position and the cover is in closed position for precluding opening movement of the cover so long as the switch is in open position.

9. Switch mechanism comprising a housing having an opening therein, a switch member pivotally mounted in the housing, a cover for closing the opening in the housing and means carried by the cover for interlocking with the switch, so related therewith 15 that the switch and cover may be actuated independently of the other except when the cover is in closed position and the switch in open position.

10. Switch mechanism comprising a hous-

ing having a switch compartment movable 20 to open and to closed positions, a fuse compartment, a switch within the switch compartment, a fuse within the fuse compartment, a separate movable cover closing each compartment, means associated with 25 the switch for retaining the cover for the switch compartment in closed position when the switch is open and for retaining the cover for the fuse compartment in closed position when the switch is in closed position, 30 and for retaining both covers in closed position when the switch is in a position intermediate extreme open and closed positions.

In testimony whereof, I have hereunto 35 subscribed my name this 14th day of September, 1920.

LAWRENCE F. KRIES.
